COOLING DEVICE FOR PISTON-RODS.

No. 821,640.

Specification of Letters Patent.

Patented May 29, 1906.

Application filed May 17, 1905. Serial No. 260,842.

To all whom it may concern:

Be it known that I, RUDOLF HARTWIG, a subject of the German Emperor, and a resident of 34 Hohenzollernstrasse, Essen-on-the-
5 Ruhr, Germany, have invented certain new and useful Improvements in Cooling Devices for Piston-Rods, of which the following is a specification.

The present invention relates to cooling devices for piston-rods, and in particular to piston-rods of internal-combustion engines.

It is a common expedient in explosion-engines to provide the piston-rods with a longitudinal bore through which a cooling medium is caused to flow. In such devices, however, the temperature of the outer wall of the piston-rod, which is directly exposed to the action of the explosive gases, becomes considerably higher than the temperature of 15 the wall of the bore in the rod, and these differences in temperature create tensions in the piston-rod which are liable to cause the rod to break.

The object of the present invention is to 20 provide a cooling device in which the drawback as above set forth is avoided.

In the accompanying drawings one embodiment of the invention is illustrated by way of example.

25 Figure 1 is a top view, partly in section, of the improved cooling device and parts of an engine. Fig. 2 is a longitudinal section, on an enlarged scale, of parts that are shown in plan in Fig. 1; and Fig. 3 is a side elevation of 30 the left-hand end of Fig. 2 in a plane at right angles to the plane of Fig. 2.

The piston-rod B of the piston A passes through the two cylinder-heads C' of the working cylinder C and has one of its ends 35 connected to the cross-head D. One of the wrists d' of the cross-head D is provided with an axial perforation or inlet d'', Fig. 2, which communicates with a longitudinal bore B' in the piston-rod B through the medium of a 40 transverse passage b³ in the piston-rod. The perforation d'' also communicates with a curved pipe E. The bore B' is closed toward the exterior by means of a screw-plug M, Fig. 2, terminates in the part of the piston-rod that is surrounded by the piston, and 45 communicates with an annular chamber a' in the piston A through a transverse outlet-passage b⁶, Fig. 2. Into the chamber a' opens a second transverse passage or inlet b⁷, which

50 communicates with a bore B² coaxial with the perforation B', but located in that part of the piston-rod extending from the opposite side of the piston and opening into an outlet-pipe Q, Figs. 2 and 3, that curves downwardly from the free end of the piston-rod. 55 To the curved pipe E is secured a pipe F, Fig. 1, that extends parallel to the piston-rod and projects into a reservoir G, which communicates with a conduit H, that may lead to a force-pump (not shown in the drawings) or 60 other suitable source of cooling medium under pressure. The pipe F is of sufficient length to continuously remain in connection with the reservoir G during the working of the engine. 65

On each side of the piston A and around the piston-rod B are arranged tubular mantles J and J', having their ends provided with inwardly-extending flanges i² i³ and i⁴ i⁵, respectively, Fig. 2, of which the flanges i² and 70 i⁴ near the piston A are screw-threaded and engage screw-threads on the piston-rod, while the outer flanges i³ and i⁵ have cylindrical inner faces tightly fitting the outer faces of the piston-rod. This arrangement 75 permits of the free expansion of the mantles J J' when they become heated by the explosion. The mantles J and J' pass tightly through stuffing-boxes c² in the cylinder-covers and are of sufficient length to remain 80 in engagement with the stuffing-boxes in the end positions of the piston within the cylinder. The above-described arrangement and form of the mantles J J' leave a hollow space K and K', Fig. 2, between each mantle and the 85 piston-rod B, through which space the cooling medium is caused to pass. To that end communication is provided between the hollow space and the perforation B' through the medium of passages b⁴ and b⁵, located in proximity to the ends of the mantle J and the outlet and the inlet of the perforation B', and likewise between the hollow space K' and the perforation B² through the medium of passages b⁸ and b⁹ near the inlet and the outlet 90 of perforation B². 95

In order to cause the greater part of the cooling medium to pass through the hollow spaces K and K', plugs N and P, which are provided with a narrow perforation n' and p', are arranged in the perforations B' and B² in the proximity of the passages b⁴ and b⁸. 105

The medium for cooling the piston-rod,

which may be water or other suitable fluid, passes from the conduit H into the reservoir G and through the pipe F, the curved pipe E, and the passages d^3 and b^3 to the part of the 5 perforation B' in the piston-rod that is in front of the plug N. From the said part of the perforation B' the greater part of the cooling medium flows through the passages b^4 to the hollow space K and from there 10 through the passages b^5 into the part of the perforation B' that is between the plug N and the passage b^6 , while a minor part of the cooling medium flows through the perforation n' in the plug N and prevents stagnation of the 15 cooling medium in the part of the perforation that is between the plug N and the passages b^5 . From the perforations B' the cooling medium flows through the passage b^6 into the annular space a' in the piston and from 20 there through the passage b^7 into the part of the perforation B^2 that is in front of the plug P. From the said part of the perforation B^2 the greater part of the cooling medium flows through the passage b^8 into the hollow space 25 K' and from there through the channels b^9 into the part of the perforation B^2 that is behind the plug P, while the minor part of the cooling medium flows through the perforation p' in the plug P. Finally, the combined 30 cooling medium flows through the pipe Q into a reservoir arranged beneath the path of travel of the pipe. (Not shown in the drawings.)

Having thus described the invention, the following is what is claimed as new therein:

- 35 1. The combination with a longitudinally-bored piston-rod, of a mantle surrounding the same and spaced therefrom, an inlet for the cooling medium at one end of the rod, and an outlet at the other end of the rod, the rod being provided with a passage connecting the bore in the rod with the mantle near the cooling-medium inlet, to provide a flow in the same direction through the rod and the mantle.
- 40 2. The combination with a longitudinally-bored piston-rod, of a mantle surrounding the same and spaced therefrom, an inlet for the cooling medium at one end of the rod, an outlet at the other end of the rod, the rod being provided with a passage connecting the bore in the rod with the mantle near the cooling-medium inlet and a passage connecting the mantle-space with the rod-bore near the outlet of said medium, to provide a flow in the same direction through the rod and the mantle.
- 45 3. The combination with a longitudinally-bored piston-rod, of a mantle surrounding the same and spaced therefrom an inlet for the cooling medium at one end of the rod, an outlet at the other end of the rod, the rod being provided with a passage connecting the bore in the rod with the mantle near the cooling medium inlet, and a passage connecting the mantle-space with the rod-bore near the 55 outlet of said medium.
- 60 4. The combination with a longitudinally-bored piston-rod, of a mantle surrounding the same and spaced therefrom, means securing said mantle to said rod by one end only and thus permitting the mantle to expand freely, and means for passing a cooling medium through the space between the mantle and the piston-rod.
- 65 5. The combination with a longitudinally-bored piston-rod, of a mantle surrounding the same and spaced therefrom, an inlet for the cooling medium at one end of the rod, an outlet at the other end of the rod, the rod being provided with a passage connecting the bore in the rod with the mantle near the cooling medium inlet, and a passage connecting the mantle-space with the rod-bore near the

outlet of said medium, to provide a flow in the same direction through the rod and the mantle, and means between the two passages for retarding the flow through the rod.

4. The combination with a longitudinally-bored piston-rod, of a mantle surrounding the same and spaced therefrom, an inlet for the cooling medium at one end of the rod and an outlet for the cooling medium at the other end of the rod, the rod being provided with a transverse passage connecting the bore and the mantle-space near the inlet and inclined in one direction, and with an oppositely-inclined transverse passage connecting the mantle-space and the bore near the outlet. 70

5. The combination with a hollow piston, of a piston-rod extending from opposite sides of the piston and provided with two longitudinal bores, a mantle surrounding each projecting portion of the rod, and spaced therefrom, communication between each bore and the hollow piston, a cooling-medium-supply pipe connected to one end of the piston-rod and its bore, and an outlet-pipe connected to the other end of the piston-rod and its bore, 85 the piston-rod being provided with transverse passages connecting the bores with the mantle-spaces near each end of each mantle. 90

6. The combination of a longitudinally-perforated piston-rod, a perforated plug fitted in the perforation, a mantle surrounding the rod and spaced therefrom, and transverse perforations in the rod leading to the space between the mantle and the rod. 95

7. The combination with a piston-rod, of a mantle spaced from the rod to provide a cooling-chamber, said mantle being secured at one end to the rod and having its other end free to expand and contract and provided with a flange tightly fitting the piston-rod. 100

8. A cooling device for longitudinally-perforated piston-rods comprising a mantle surrounding the rod and spaced therefrom, means providing communication between the longitudinal perforation of the piston-rod and the space between the mantle and the rod, means for supplying a cooling medium to the rod and means for permitting a part of the cooling medium to pass through the rod without going through said intermediate space. 110

9. A cooling device for piston-rods comprising a mantle surrounding the rod and spaced therefrom, means securing said mantle to said rod by one end only and thus permitting the mantle to expand freely, and means for passing a cooling medium through the space between the mantle and the piston-rod. 120

The foregoing specification signed at Düsseldorf this 3d day of May, 1905.

RUDOLF HARTWIG.
